UNITED STATES PATENT OFFICE.

CHARLES A. MOORE, OF ST. PAUL, MINNESOTA, ASSIGNOR TO MOORE PATENT CAR CO.,
A CORPORATION OF MINNESOTA.

REFRIGERATOR-CAR.

1,030,524.

Specification of Letters Patent. Patented June 25, 1912.

Application filed June 14, 1907. Serial No. 379,094.

To all whom it may concern:

Be it known that I, CHARLES A. MOORE, a citizen of the United States, residing at St. Paul, in the county of Ramsey and State 5 of Minnesota, have invented a new and useful Improvement in Refrigerator-Cars, of which the following is a specification.

My invention relates to improvements in refrigerator cars which are cooled, heated 10 and ventilated.

The primary object attained by this invention is the maintenance of a sufficiently low temperature within the car when the outside atmosphere is warm and of a temperature 15 above freezing when the outside atmosphere is below.

Further objects are to provide an efficient and effective system of internal air circulation and the largest surface for cooling or 20 heating the atmosphere in the smallest possible space whereby the dimensions of the inclosure are least encroached upon by the room taken up by the apparatus.

Depending in part upon these requirements I provide in the car inclosure an ice 25 bunker between the ends of the car and extending from the floor to the roof thereof and means for raising the temperature of the air within the car and circulating said 30 air in an effective manner.

My invention further consists of the features, details and combinations of parts hereinafter described and claimed.

In the accompanying drawings, forming 35 part of this specification, Figure 1 is a longitudinal sectional view of a portion of a refrigerator car illustrating my invention; Fig. 2 is a plan view partly in section taken on the line A—A of Fig. 1; Fig. 3 is a 40 cross section of Fig. 1 taken on the line B—B; Fig. 4 is another cross sectional view of Fig. 1 taken on the line C—C; Fig. 5 is a longitudinal sectional view of a portion of a refrigerator car illustrating an alternative 45 construction of my invention, and Fig. 6 is a cross sectional view of Fig. 5 taken on the line D—D and showing a portion of the ice bunker broken away. The car body proper, that is, its sides E, roof F, ends G and 50 floor H is made in any desired form and I do not limit the application of my particular improvements to the special and general construction shown in the drawings. The sides, flooring, ends and roof of the car are 55 preferably made double, treble, or quad- ruple, with any desired number of dead air spaces I, between the separate portions of the walls, which air spaces may, if desired, be filled with any suitable material which will serve to insulate the interior of the car. 60 The inner spaces J however, are not filled with any material and are adapted to conduct the hot and cold air issuing from the heating chamber K and ice bunker L into the car. 65

The ice bunker L is located substantially midway between the ends of the car and extends from the floor to the roof. This bunker has an overhead tray 2 extending across, immediately below and spaced from 70 the roof of the car, the tray being supported by transverse and longitudinal I-beams 3. The ends of the transverse I-beams are set in the sides of the car and the intersections of all of the beams are connected by means 75 of angle bolts 4 which are secured thereto by rivets 5. Floor planks 6 are supported by the I-beams, and angle slats 7 are placed above the floor planks upon space bars 8. The angle irons are sufficiently spaced apart 80 so as to permit water to drip from the ice in the bunker between the slats and upon the floor of the tray from where it is conducted below the car by means of drip pipes 9. A section 10 of the tray is made removable 85 for the purposes to be hereinafter described. The ends of the overhead ice bunker M are provided with downwardly and inwardly inclined horizontal slats 11 which are spaced apart so that air is free 90 to circulate between the provision chamber in the car and the overhead ice bunker. It is understood that the ends of the overhead ice bunker are of construction similar to each other, the drawings illustrating but 95 one end. Below the tray of the overhead ice bunker is a lower ice bunker N which extends downwardly to the floor of the car. This lower ice bunker as shown has side walls 12 which are spaced from the sides of 100 the car leaving a passageway for the loading and unloading of the car through the doorway 13. The ends of the lower bunker are constructed by vertical posts 14 having wire meshing 15 fastened outside and transverse downwardly and inwardly inclined slats 16 which are spaced apart and fastened between said posts. Near the bottom of the lower ice bunker is a horizontal grating 17 which supports the ice and allows air to 110

circulate downwardly through the bunker and the water to drip from the ice below it. Spaced below the grating so that air is free to circulate downwardly through the lower ice bunker and into the provision chamber is a downwardly and inwardly inclined drip pan 18 which catches the water dripping from the ice and conducts it from the car through a downwardly directed vent 10 pipe 19.

In the roof of the car and immediately above the upper ice bunker M are hatchways 20 through which ice is adapted to be placed in the lower and upper ice bunkers, it being understood that when the lower ice bunker is iced the section 10 of the tray is removed through one of the hatchways or placed at one side of the upper ice bunker. By this means the disposition of the ice in the ice bunker is arranged so that either part or all of the ice bunker can be used and when it is desired to keep the ice near the roof of the car and maintain only part of the bunker in operation, the section 10 of the tray can be inserted in place. The lower ice bunker as shown is adapted to expose a larger area of ice to the atmosphere in the provision chamber than the upper section.

The ventilating passageway J connects 30 with the top of the upper ice bunker and leads into the provision chamber by the openings 21. In this manner the air in all portions of the car is circulated through the ice bunker. The lower end of the air vent 35 tilating passageway J connects with the upper portion of the heating chamber K which is supported below the floor and substantially midway between the ends of the car. This heating chamber is provided with a heater 22 and a door 23 by which access is 40 had into the heating chamber for the purpose of operating the heater.

The heater is of ordinary construction and the heating chamber has air inlets 24 45 through which fresh air passes into the heater and up into the provision chamber of the car and the ice bunker. The roof above the upper ice bunker has an air vent 25 leading to the outer atmosphere for the 50 purpose of ventilating the car.

In the alternative construction, the lower ice bunker N extends across the provision chamber and connects between the sides of the car and is particularly adapted for use 55 with a car having doorways 26 near each of its ends instead of midway between ends as shown in the preferred construction. The length of the ice bunker is considerably less than the length used in the preferred construction, otherwise the parts are of substantially similar construction except that the slats 16 and wire meshing 15 are used in the ends instead of the side walls of the bunker.

60 In operation, when it is desired to cool

the atmosphere in the car ice is placed in the lower and upper bunkers through the hatchways in the roof which are afterward sealed. The cold air from the bunkers passes into the car through the open-work 70 walls of said bunker and the air conducting passageway J. When it is desired to heat the car, the heater 22 is operated. Air then freely circulates around the heater from the passageways 24 and up into the car through 75 the conducting passageway J and port openings 21. It also enters the car through the ice bunker. In this manner warm or cold air freely circulates through the car when the heater or refrigerator is in operation. 80 When desired, the inlets 24 may be provided with valves 28 so that the admission of fresh and cold air into the car can be controlled. To increase the ventilation of the car the ventilator 25 can be opened when the heater, 85 refrigerator, or both are in or out of operation.

In accordance with the patent statutes, I have described the principle of operation of my invention, together with the apparatus 90 which I now consider to represent the best embodiment thereof, but I desire to have it understood that the apparatus shown is only illustrative and that the invention can be carried out by other means and applied to 95 uses other than those above set forth, within the scope of the following claims.

Having described my invention, what I claim as new and desire to protect by Letters Patent, is:—

1. A refrigerator car, comprising, in combination, a car body having a roof substantially straight throughout the length of the car and a provision chamber extending entirely from end to end thereof, an ice bunker 105 immediately below the roof and having ends remote from the ends of the car opening into the top of the provision chamber for the circulation of air, said bunker having a longitudinal upper portion and an auxiliary 110 lower portion extending from the floor of the provision chamber to the floor of the upper portion of said bunker, an ice grate in the lower portion of said bunker, a hatchway entering said bunker through the roof 115 of the car and a removable tray section in the floor of said bunker between the upper and lower portions of said bunker, whereby the ice can be confined to the upper portion of said bunker adjacent the roof of the car 120 or by the removal of said tray section held in the entire bunker.

2. A refrigerator car, comprising, in combination, a car body having a roof substantially straight throughout its length and a 125 provision chamber extending entirely from end to end thereof, an ice bunker immediately below the roof of the car having ends remote from the ends of the car and opening directly into the top of the provision 130

chamber for the free circulation of air and having an apertured floor, a removable tray section fitted to the aperture in said floor, and a second ice bunker below said floor and 5 in said provision chamber adapted to receive ice from said first bunker in the open position of said tray.

3. A refrigerator car, comprising, in combination, a car body having a roof substantially straight throughout its length and a provision chamber extending entirely from end to end thereof, an ice bunker immediately below the roof of the car having both ends remote from the ends of the car 10 and extending the entire inside width of the car body and provided with upright ends

opening directly into the top of the provision chamber for the free circulation of air, a hatchway in the roof of the car over said ice bunker, and a second ice bunker having 20 a median position in said provision chamber below said first bunker and communicating therewith through an aperture in the floor thereof.

In testimony whereof, I have signed my 25 name to this specification, in the presence of two subscribing witnesses.

CHARLES A. MOORE.
